UNITED STATES PATENT OFFICE.

JOHN WILLIAM DIRHOLD, OF ST. LOUIS, MISSOURI.

CLAMP FOR RULING-PENS.

SPECIFICATION forming part of Letters Patent No. 295,370, dated March 18, 1884.

Application filed May 18, 1883. (Model.)

To all whom it may concern:

Be it known that I, JOHN WILLIAM DIRHOLD, of St. Louis, in the county of St. Louis and State of Missouri, have invented a new and useful Improvement in Clamps for Ruling-Pens; and I do hereby declare that the following is a full, clear, and exact description of the same.

The invention is an improvement in the class of ruling-machines in which the pen-holders are moved laterally in parallel position by means of a system of levers connected by pivots, so as to form a lazy-tongs.

The invention consists in the combination and arrangement of parts hereinafter described and claimed.

In the accompanying drawings, Figure 1 is a plan view of the clamp, a portion of the body being broken out to show the arrangement of mechanism interiorly. Fig. 2 is a vertical cross-section of the same.

The body of the clamp is formed of two parts, A A', which are chambered and secured together at the sides in such a manner that they are held separated at the front-edge, thus leaving a narrow space, a, through which the pen-holders C project. Each of the latter is a thin slotted bar, and all are arranged parallel to each other and at right angles to the longer axis of the clamp. Each holder C has a lug, d', which enters and slides in a slot, a', formed in the inner side of the part A', and extending lengthwise thereof.

The system of levers B for adjusting the pen-holders C is arranged and connected after the manner of a lazy-tongs, and one end of the system is secured to the body of the clamp at b. Near the other end of the system is attached a long pin, that projects through a lateral slot, f, in the base A of the clamp, and has a knob or button, b', and also carries a pointer, g, which indicates on a scale, h, the extent of movement and position of the pen-holders C. Screws or pins d connect the levers B together, and also pass through and work in the slots of the pen-holders C, so that

the latter are moved laterally together and held parallel during such movement. Metal plates E E are attached to the ends of the clamp, and hooks e e are connected therewith, those at one end being screw-threaded to permit adjustment. Wires e' e', having loops at their ends, are engaged with the hooks e e, and extend across the levers B and holders C to support them within the chamber of the clamp, as shown in Fig. 2. Bands c serve to secure the pens c' detachably to the ends of the holders C, that project through the groove a in the clamp.

The operation is as follows: When it is desired to move the pens e' for the purpose of bringing them nearer together or moving them farther apart, the head b', carrying the pointer g, is moved in the groove f to a position opposite the proper point in the scale h. By this action the system of levers B is actuated, in the manner well understood, to cause the holders C to approach or recede from each other, according to the direction of the movement. As each holder projects through and moves in the guiding-groove a, it follows that all are held in the same longitudinal position. As each holder also engages with two of the screws d of the levers, which are located upon opposite sides of a center line, it follows that a perfectly parallel movement is insured.

Having thus described my invention, what I claim as new is—

1. The combination, with the hollow body of the clamp and the system of movable levers and pen-holders, of the wires e' e', which are stretched taut and support said levers and holders, as shown and described.

2. In combination with the body of the clamp, having grooves a f and scale h, the system of levers B, with head b' and pointer g, the slotted holders C, the screws d, and the securing-wires e' e', as described.

JOHN WILLIAM DIRHOLD.
